(57) **CLAIM**

The ornamental design for a pressurized air manifold with regulator, as shown and described.

DESCRIPTION

FIG. 1 is a perspective view of a pressurized air manifold with regulator showing my new design;

FIG. 2 is a top view thereof;

FIG. 3 is a bottom view thereof;

FIG. 4 is a front view thereof;

FIG. 5 is a back view thereof;

FIG. 6 is a right side view thereof; and,

FIG. 7 is a left side view thereof.

In the drawings, the broken lines depict environmental subject matter only and form no part of the claimed design.
